UNITED STATES PATENT OFFICE.

JACOB A. HYLE, OF HARRISBURG, PENNSYLVANIA, ASSIGNOR OF ONE-THIRD TO THEODORE F. VON DORN AND ONE-THIRD TO JAMES A. TWITCHELL, BOTH OF NEW YORK, N. Y.

RAILWAY-TIE.

1,145,141.

Specification of Letters Patent.

Patented July 6, 1915.

Application filed April 26, 1915. Serial No. 24,098.

To all whom it may concern:

Be it known that I, JACOB A. HYLE, a citizen of the United States, residing at Harrisburg, in the county of Dauphin and State of Pennsylvania, have invented certain new and useful Improvements in Railway-Ties, of which the following is a specification.

My invention relates to an improved railway tie for steam and electric railways of various kinds.

The main object of my invention is to provide a simple, durable, economical and efficient metal railway tie possessing sufficient strength to successfully withstand the strains to which the tie is subjected when in service and which is so constructed that water will not collect and remain in the tie, thereby increasing the longevity of the same.

Another object of the invention is to provide a combined metallic and concrete or asphaltum railway tie, in connection with wooden blocks forming a support for the track rails, and constituting a thorough and reliable insulation of the rails so as to render them effective as conductors in the usual automatic electrical signaling systems.

A further object of this invention is to so construct a metallic railway tie that it will be prevented from lateral and longitudinal movement or skidding action during the passage of the rolling stock over the track rails. And still further objects of the invention are to so construct a metallic railway tie whereby one or both of the wooden blocks used in connection therewith may be readily removed therefrom and a new one placed therein without removing the tie, or in any manner disturbing the position or location of the track rail or ballast beneath the tie; to provide improved means for securing the wooden blocks to the tie whereby absolute safety in the gage of the track rails is maintained, and to secure the track rails in place upon the wooden blocks by means of the ordinary rail-fastening devices of the kind now in general use and ordinarily employed for the purpose of securing the rails to a wooden tie.

The foregoing and such other objects as may occur from the ensuing description, are attained by the means hereinafter more fully described, and by the combination, construction, arrangement and location of the parts such as illustrated in the accompany-

ing drawings and particularly set forth in the claims appended hereto.

Reference now being had to the accompanying drawings which form a part of this specification and in which similar numerals of reference indicate like parts throughout the several views, it will be seen that Figure 1, illustrates a plan view of the improved railway tie embodying my invention. Fig. 2, represents a longitudinal section taken on the line 2—2, Fig. 1. Fig. 3, is a transverse section taken on the line 3—3, Fig. 1. Fig. 4, is a plan view of the central portion of the tie, each end portion being broken away and the concrete or asphaltum removed, and Fig. 5, is a perspective view showing one of the block securing clamps removed from the tie.

In carrying out my invention I provide a railway tie of suitable dimensions throughout its length and breadth and the metallic portion of said tie with which my invention is embodied in the form illustrated in the drawings, comprises a metallic shell preferably formed from a sheet of any suitable or desirable metal bent up into substantially a trough shape, with vertical sides 1 and a substantially flat bottom portion 2. This trough shaped metallic shell, by reason of its form, is substantially rigid and yet possesses a sufficient inherent resiliency to relieve the rolling stock from vibrations incident to an absolute rigid bed, but in order to augment this effect, as well as to secure advantages which will be readily apparent to those skilled in the art, the track rails are not supported directly on the metal portion of the tie but are preferably seated on a metal plate 3, which rests upon the upper surface of a wooden block 4 said block projecting a suitable distance above the metallic tie, one block located near each end of the tie, and said blocks 4 are fitted into the trough-shaped body portion of the tie in proper position with relation to the ends of the tie for receiving the rails, the size of the blocks being sufficient to afford the necessary strength to support the rails and retain the rail fastening means such as nail or screw-threaded spikes ordinarily employed for securing the track rails in place.

The wooden blocks employed are first impregnated with oil or creosote to increase their durability and are preferably con-

structed rectangular in cross-section and adapted to fit accurately in the trough-shaped body of the tie, if desired, the dimensions being uniform so that the blocks 5 may be turned up-side-down or either side 10 may be utilized as the top or rail supporting surface. The said wooden blocks project a suitable distance above the upper portion 15 of the metallic tie, as clearly shown in Figs. 2 and 3, thus properly insulating the track 20 rails from the metallic tie at all times, and preventing contact therewith. The blocks are rigidly and securely clamped in place by fastening means which extend entirely 25 around the outside of the tie body and are securely riveted to the bottom portion of the tie and by bolts passing entirely through the blocks above the top of the said tie body.

The fastening means preferably employed 20 for firmly securing each block within the body portion of the tie consist of two upright metallic bars or clamps 5, one secured at either side of the track rail 6 to the bottom portion of the tie by a plurality of 25 rivets 7, each bar or clamp extending around the tie and being provided with an inwardly projecting shouldered portion 8 adapted to overlap the upper edge of the tie and having inwardly projecting overlapping terminal 30 portions 9, adapted to rest in contact with the upper surface of the block. Passing through the perforations 10 in each of the said bars or clamps 5 and the perforations 35 through the block above the upper portion of the tie are the two bolts 11, one end of each bolt being screw-threaded and provided with a securing nut 12. By the use of the block 40 fastening means hereinbefore referred to, it will be seen that there can be no shifting movement of the blocks without moving the entire tie and track rail supporting means thereby insuring and maintaining the proper gage of the track rails.

It will be perceived that the clamps 5 are 45 away from contact with the base of the rail and that by forming the shoulders 8, on each of the clamps, the said clamps are permitted to contact with the side faces of the wooden block, so that when the bolts 11 are passed 50 through the blocks above the body of the tie and secured by the nuts 12, the said blocks are so firmly compressed together near their top portion by the bolts and clamps as to prevent the liability of the splitting of the 55 blocks by driving the fastening spikes therein, at the same time the clamps and plurality of fastening rivets projecting below the bottom of the tie serve to prevent both lateral and longitudinal movement of the said tie.

60 The bottom portion of the tie near each side thereof is provided with a series of depending projections 13, arranged in staggered relation to each other and formed by punching openings 14 through the metal 65 leaving a plurality of depending roughened

portions around each opening, which depending portions together with the bars or clamps 5, and rivets 7, which project into the road bed or track ballast serve to prevent any lateral, longitudinal movement or skidding action of the railway ties during the strains to which they are usually subjected. 70

In order to increase the weight and ballasting qualities of the tie, it is preferably 75 filled with concrete or asphaltum between the wooden blocks, and a plurality of Z-shaped upright projections 15 are riveted to the inside of the tie which serve together with the openings in the bottom of the tie to lock the concrete or asphaltum within the 80 tie while in use or when being shipped or moved from one place to another.

If desired the concrete or asphaltum and the Z-shaped projections may be omitted, the 85 openings in the bottom of the tie then serving to drain off all water and moisture from the inside of the tie, thus increasing the longevity of the same.

It will be evident that with a structure 90 of the character such as shown and described, that when desired, the ordinary watering troughs may be arranged and supported upon the upper surface of the ties between the track rail supporting blocks without fear of projecting too high above 95 the track bed. It will further be seen that all of the parts are securely locked together serving to effectively prevent spreading of the track rails and the tie is furnished with sufficient weight to prevent creeping, etc. It 100 will also be readily perceived that with a structure of the character herein set forth, that if the blocks should rot or become unfit for further use they can be replaced without the employment of a number of men or experts, since any laborer can, after the removal of the ballast, which it will be understood fills the space in the tie between the wooden block and the outer end of the tie, withdraw the bolts and spikes, knock the 110 block out of place and replace it by a new one, and reinsert the bolts, or lag screws should there be no perforations through the new block, without in any manner disturbing the position or location of the tie, track 115 rails or ballast, so that by keeping the road bed entire and without disturbing the surface of the track is comparatively inexpensive.

It will be understood that the metal plate 120 3 which rests upon the upper surface of the wooden block constituting a seat for the track rail may be entirely dispensed with, if desired, and the rail seated directly upon the upper surface of the block. 125

It will be obvious that slight changes in the details of construction herein described may be resorted to without departing from the spirit of my invention.

Having thus described my invention what 130

I claim and desire to secure by Letters Patent is:—

1. A railway tie comprising a metallic plate having vertical side flanges, separated 5 upright clamps surrounding the tie adapted to receive the rail between them provided with openings above said side flanges for the passage of transverse bolts and rigidly secured to the bottom of the tie, a block 10 fitted between said vertical side flanges and projecting above the same, and provided with openings above the tie to receive the transverse bolts passing through the clamps and blocks for securely fastening the block 15 within the tie.

2. A railway tie comprising a metallic plate having vertical side flanges, a wooden block fitted between said vertical side flanges near each end of the tie and projecting above said side flanges, a plurality 20 of upright clamps surrounding the tie and rigidly secured to the bottom thereof, having inwardly extending shoulders adapted to rest on the upper surface of the side 25 flanges and each clamp terminating at its upper end with inwardly projecting portions adapted to overlap and contact with the upper surface of the block, said clamps and blocks being provided with openings 30 above the side flanges of the tie to receive transverse bolts for securely fastening the blocks within the tie.

3. A railway tie comprising a metallic plate having vertical side flanges, a wooden block fitted between said vertical side flanges near each end of the tie and projecting above said side flanges, a plurality 35 of upright clamps rigidly secured to the bottom of the tie, transverse bolts passing through said clamps and blocks above the vertical sides for securely fastening the blocks within the tie, a filling of concrete 40 or asphaltum between the vertical sides, and means in the bottom of the tie and secured 45 within the tie to lock and retain the said concrete in position.

4. A railway tie comprising a metallic plate having vertical side flanges, a wooden block fitted between said vertical side flanges 50 near each end of the tie and projecting above said side flanges, a plurality of upright clamps rigidly secured to the bottom of the tie and having openings above the side flanges to receive fastening bolts, and 55 a series of staggered integral projections depending from the bottom of the tie, a filling

of concrete between the blocks, and means formed in the bottom of the tie and secured within the tie to lock and retain the filling of concrete therein. 60

5. A railway tie comprising a metal trough-like body, independent wooden blocks fitted in the body near each end thereof and projecting above the body, a plurality of upright clamps extending around 65 the said body securely fastened to the bottom portion and provided with inwardly projecting shoulders adapted to contact with the upper portion of the body, the terminal end portions of each clamp adapted to overlap and rest in contact with the upper surface of the wooden block, and bolts adapted 70 to pass transversely through the said clamps and blocks above the said body for rigidly securing the said blocks to the body. 75

6. A railway tie comprising a metal trough-like body, independent wooden blocks fitted in the body near each end thereof and projecting above the body, a plurality of upright clamps extending around the 80 said body firmly secured to the bottom thereof, the terminal end portions of each clamp having inward projections adapted to overlap and contact with the upper surface of the wooden block, a filling of concrete with- 85 in the body between the said blocks, means formed in the bottom of the tie and secured within the tie to lock and retain the concrete filling therein, and bolts passing transversely through the said clamps and blocks 90 above the said body for rigidly securing the said blocks within the body.

7. A railway tie comprising a metal trough-like body, independent wooden blocks fitted in the body near each end 95 thereof and projecting above the body, a plurality of upright clamps extending around the body and firmly secured to the bottom thereof, the terminal end portions of each clamp being adapted to overlap and 100 contact with the upper surface of the block, and bolts passing transversely through the said clamps and blocks above the said body for rigidly securing the wooden blocks within the body. 105

In testimony whereof I affix my signature in presence of two witnesses.
